UNITED STATES PATENT OFFICE

2,521,409

ADJUSTABLE MATERNITY SKIRT

Paula Richony, Beverly Hills, Calif.

Application August 30, 1948, Serial No. 46,919

3 Claims. (Cl. 2—221)

This invention relates to adjustable dress skirts for pregnant women, and the primary object of the invention is to provide a skirt of this kind whose style or appearance is substantially unaltered despite the gradual enlarged adjustment thereof in the progressive stages of pregnancy.

Another object is to provide a maternity skirt the upper portion of the front of which, or that portion which overlies the abdomen, is readily adjustable in girth and of cupped form to comfortably accommodate the enlarged abdomen of a pregnant woman, whereby material lifting of said front portion and consequent destruction of the original style or balanced effect of the skirt is eliminated, and whereby the enlarged condition of the woman's abdomen is rendered less obvious or conspicuous.

The exact nature of the present invention as well as other objects and features thereof will become apparent from the following description when considered in connection with the accompanying drawings, in which:

Figure 1 is a front perspective view of a maternity skirt embodying the present invention, as said skirt appears while being worn;

Figure 2 is an enlarged side elevational view thereof;

Figure 3 is an enlarged rear elevational view of the same with the upper portion of the back folded backwardly and downwardly;

Figure 4 is an enlarged fragmentary horizontal section taken on line 4—4 of Figure 3;

Figure 5 is a horizontal section taken on line 5—5 of Figure 2; and

Figure 6 is an enlarged fragmentary vertical section taken on line 6—6 of Figure 5.

Referring in detail to the drawings, the illustrated embodiment of the invention consists of a front 5 and a back 6 sewed together along the major lower portions of their adjacent side edges, as at 7, and having the upper portions of said edges left free to form side plackets at 8 adapted to be adjustably secured in closed position by means of coacting separable fastener elements 9 and 10. The upper portion of the back may have flap extensions 11 on its side edges which are adjustably and separably connected at and inwardly of the front 5 of the skirt by means of tapes 12 adapted to be tied in a bow as at 13. Also, the upper portion of the back may be provided with permanent pleats 14 to provide the usual fullness thereof directly below the waist line.

At each side of the vertical center of the front 5, the upper portion of said front is provided

with a plurality of vertical, downwardly tapered temporary pleats 15 which are tacked or basted to permit ready selective release and unfolding thereof, so as to gradually increase the girth of the garment at and immediately below the waist line and to originally give said upper portion of the front a cupped form, as shown at 16. The expansion of the upper portion of the front may be yieldingly opposed by an elastic strap 17 secured at its ends to said portion adjacent the side edges of the latter and extending across said portion near the waist line and through a series of loops 18 formed by attaching a zigzag length of tape at spaced points to the front. While both 15 the flaps 11 and tapes 12 and the elastic strap 17 and loops 18 have been shown, it will be apparent that either the elements 11 and 12 or the elements 17 and 18 may be omitted.

The cupped form of the upper portion of the front at 16, which overlies the abdomen, renders the enlarged condition of the latter less obvious or conspicuous. The tacked pleats 15 may be successively released as the abdomen becomes larger to permit expansion of the upper portion 25 of the skirt for the wearer's comfort. These features, together with the elements 11 and 12 and/or the elements 17 and 18 prevent lifting of the front portion of the skirt and consequent destruction of the original style or balanced effect 30 of the skirt, as the abdomen becomes larger.

In donning the skirt, the tapes 12 are untied and the plackets at 8 are unfastened. The extensions 11 and tapes 12 are then brought around the front of the wearer inwardly of the upper 35 front portion of the skirt, and the tapes 12 are then tied together. The plackets are then fastened in closed position by means of the fastener elements 9 and 10.

From the foregoing description, it is believed 40 that the construction and advantages of the present invention will be readily understood and appreciated by those skilled in the art. Modifications and changes in details of construction are contemplated, such as fairly fall within the spirit and scope of the invention as claimed.

Having described the invention, what is claimed as new is:

1. A maternity skirt including a front having its upper portion of outwardly cupped form to accommodate the abdomen when enlarged by reason of pregnancy, said upper front portion having a plurality of vertical downwardly tapered temporary pleats tacked as to be readily releasable and unfoldable to gradually increase the girth 55 of the skirt at and immediately below the waist

line, and elastic means secured on the inside of said upper front portion adjacent the waist line to yieldingly oppose expansion of said portion by unfolding of the released pleats.

2. A maternity skirt comprising a front and a back sewed together along the major lower portions of their adjacent side edges and having the upper portions of said edges free to form a placket at each side of the skirt, the upper portion of said front being of outwardly cupped form and having a plurality of vertical temporary pleats tacked so as to be readily releasable and unfoldable to gradually increase the girth of the skirt at and immediately below the waist line thereof, releasable means to close said plackets and elastic means secured on the inside of said upper front portion to yieldingly oppose expansion thereof upon release of said pleats.

3. A maternity skirt comprising a front and a back sewed together along the major lower portions of their adjacent side edges and having the upper portions of said edges free to form a placket at each side of the skirt, the upper portion of said front being of outwardly cupped form and having a plurality of vertical temporary pleats tacked so as to be readily releasable and unfold-

able to gradually increase the girth of the skirt at and immediately below the waist line thereof, releasable means to close said plackets, a zigzag length of tape extending across and attached to the inside of said upper portion of the front to provide a horizontal series of loops, and an elastic strap attached at its ends to said upper portion adjacent its side edges and passing through said loops, said elastic strap acting to oppose expansion of said upper portion upon release of said pleats.

PAULA RICHONY.
